BOTTLE FILLING MACHINE AND VALVE
THEREFOREarl E. Schnehain, Deer Park, Ohio, assignor to The
Realistic Company, Cincinnati, Ohio, a corporation of
Ohio

Application April 28, 1954, Serial No. 426,113

8 Claims. (Cl. 226—128)

This invention relates to a machine for filling bottles. More particularly, this invention relates to a valve for a machine of this type.

Many liquids used in the waving of hair and for other purposes are so corrosive in nature that they must be handled without touching any metal.

An object of this invention is to provide a bottle-filling machine which has no metal parts which come in contact with the liquid with which bottles are filled.

A further object of this invention is to provide a valve for a machine of this type having an electrically controlled valve member which has no metal parts exposed to the liquid passing through the valve.

A further object of this invention is to provide a solenoid operated valve for a bottle-filling machine in which there are no exposed metal parts.

A further object of this invention is to provide a solenoid operated valve having a valve member which turns as liquid passes through the valve.

A further object of this invention is to provide a syphon operated bottle-filling machine having a solenoid operated valve arranged to permit flow of liquid to a bottle when the bottle is at an elevated filling position and for halting flow of liquid when the filled bottle is lowered to remove it from the bottle-filling machine.

The above and other objects and features of the invention will in part be apparent and will in part be obvious to those having ordinary skill in the art to which this invention pertains, from the following detailed description, and the drawings, in which:

Figure 1 is a view partly in side elevation and partly in section, showing a bottle-filling machine constructed in accordance with an embodiment of this invention with bottles shown in filling position, electrical connections of the machine being illustrated schematically;

Fig. 2 is a fragmentary view in front elevation of the machine illustrated in Fig. 1 with the bottles shown in lowered position;

Fig. 3 is a view partly in side elevation and partly in vertical section, showing one of the valves of the machine;

Fig. 4 is an exploded view showing the valve;

Fig. 5 is an exploded view showing a valve plug which is a part of the valve illustrated in Fig. 4;

Fig. 6 is a top plan view of the plug looking in the direction of line VI—VI in Fig. 4; and

Fig. 7 is a sectional view taken along a line VII—VII in Fig. 4.

In the following detailed description and the drawings, like reference characters indicate like parts.

As illustrated in Figs. 1 and 2, the bottle-filling machine includes a tank 10 into which liquid is fed from an inlet line 12 through a valve 13. Operation of the valve 13 is controlled by a float 14. As float 14 rises, a plunger 16 attached to the float engages a switch button 17 to actuate a switch 18. When the push button 17 of switch 18 is raised, the valve 13 closes to shut off

2

the flow of liquid to the tank 10. As liquid flows from the tank 10, the float 14 falls to permit release of the button 17. When the button 17 is released, liquid again flows through the valve 13 to restore the level of liquid in the tank 10. The switch 18 is arranged to maintain as nearly constant a liquid level 19 as possible in the tank 10.

Liquid flows from the tank 10 through syphon tubes 21 to filler valves 22 (Fig. 2). Each of the filler valves 22 is provided with a switch 23 (Fig. 1) and a switch operating lever 24. The free end of the switch operating lever 24 is disposed close to the filler valve discharge spout 26 of the valve associated therewith so that, when a bottle 27 is raised with the spout 26 projecting into the neck of the bottle, the mouth of the bottle engages the switch operating lever 24 whereby button 28 is actuated to close the switch. Closing of the switch 23 supplies electrical current to a solenoid coil 31 which actuates the valve 22 to open position.

Details of construction of the valve 22 are shown in Figs. 3 to 7 inclusive. The construction of only one of the valves will be described in detail as the valves are similar in construction and operation. As shown in Figs. 3 and 4, the valve 22 includes an upright tubular body member 33 having a vertically disposed cylindrical chamber 34. The lower end of the chamber 34 is provided with a frusto-conic valve seat 36 and the outlet for the valve chamber is below seat 36. A valve member 37 is mounted in the chamber 34 and can rise and fall inside the chamber. When the valve member 37 is in the lowered position shown in Fig. 3, a conic face 38 of the member 37 engages the valve seat 36 to close the valve.

As shown in Figs. 5-7 inclusive, the valve member 37 consists of a hollow, generally cylindrical main portion 41, a metal plug 42, and a cap portion 43. The cylindrical main portion 41 is provided with an interior chamber 44 in which the metal plug 42 is received. The metal plug 42 is formed of iron or other suitable magnetic metal which is responsive to a magnetic field set up by the solenoid winding 31. The plug 42 is held in place inside the chamber 44 by the cap portion 43. The plug 42 is completely enclosed inside the valve member 37 so that none of the liquid flowing through the valve touches the metal plug 42.

As shown in Figs. 5 and 6, the cap portion 43 is provided with a series of outwardly projecting lugs 46, and the lower end of the main portion of the valve member is provided with similar lugs 47. The lugs 46 and 47 serve to space the valve member 37 from the walls of the chamber 34 of the valve. In addition, as shown, the lugs 46 and 47 are inclined to the axis of the member 37 and form vanes projecting outwardly therefrom to impart a spinning motion to the member 37 when the valve is open and liquid flows through the valve so that valve face and valve seat wear evenly and are kept concentric to prevent leaking of the valve.

The open end of the chamber 34 of the valve is closed by a hollow cap member 49 which is threaded to the body member 33. The cap member is provided with an integral tubular portion 50 to which syphon tube 21 is attached, as shown in Fig. 1. A washer 50' forms a seal between the cap member and the body member of the valve.

The solenoid 31 is mounted on the body member 33 as shown in Fig. 3 and is held in place thereon between a collar 51, which is integral with body member 33, and a collar 52 threaded on the body member. Appropriate washers 53 and 54 are disposed on the lower and upper sides of the solenoid, and are engaged by the collars.

All the parts of the valve which come in contact with

the liquid which flows through the valve are formed of appropriate material which is non-magnetic and which is not corroded by the liquid flowing through the valve. These parts include the siphon tube 21 (see Fig. 1), the cap 49 (see Fig. 4), the cap washer 50, the exposed portions of the rotating valve member 37, and the body portion 33 of the valve. All these parts are formed of appropriate non-magnetic and non-corroding material. For example, in a machine for use in filling bottles with hair waving solution, the washer 50' may be formed of neoprene while the other parts may all be formed of a methacrylate plastic such as that commonly known as "Lucite" or other suitable non-magnetic and non-corroding material. The plug 42 may be formed of iron or other appropriate metal which is magnetizable so that it is responsive to the magnetic field of the solenoid. The plug 42 is completely enclosed and does not come in contact with liquid flowing through the valve.

When the machine is in use, bottles 27 are mounted on an appropriate chain conveyor 55 and are advanced on the chain conveyor until the bottles reach a stop member 56 (see Fig. 2). The bottles advance to the stop member 56 between guide plates 57 and 58. A Y-shaped yoke 59 having bottle-engaging arms 61 and 62, embraces the chain conveyor 55 and the guide plates 57 and 58, respectively. When the bottles are stopped in the position shown in Fig. 2, the yoke 59 is raised by means of a treadle 63 to raise the bottles with the filler spouts 26 projecting into the necks of the bottles. When the bottles are raised to the position shown in Fig. 1, the mouth of each of the bottles engages one of the switch operating levers 24 (only one of which is shown) to actuate switch 23 and cause the one of the solenoid coils 31 associated therewith to be energized.

When the solenoid coils are energized, the valve members of the valves are raised to permit liquid to be siphoned from the tank 10 to the bottles 27. The bottles are filled until the level in the bottles is the same as the level in the tank 10 and the siphon head is zero. Then, the treadle 63 is released to lower the bottles, whereupon the solenoid actuating switches are released to de-energize the solenoids and permit the valve members to descend to stop the siphoning of liquid. As the bottles are lowered, they can be visually inspected, and, if any additional liquid is needed in one of the bottles, the appropriate switch 23 may be actuated to permit flow of such additional liquid as may be required. When the bottles are lowered, stop member 56 can be swung back to the position 56a shown in dot-dash lines in Fig. 1 to permit the chain conveyor to advance the bottles from the filling position. As shown in Figs. 3 and 4, the lower end of the spout 26 of each of the valves is constricted as indicated at 67 to hold a column of liquid in the spout 26 when the valve is closed for starting the siphon action when the valve is opened again.

When each of the valves is open, the valve member thereof spins freely inside the valve to permit a smooth flow of liquid through the valve. When the solenoid is de-energized, the valve member falls to the position shown in Fig. 3 in which the valve is closed.

The bottle-filling machine and the valve therefor illustrated herein are subject to structural modification without departing from the spirit and scope of the appended claims.

Having described my invention, what I claim as new and desire to secure by letters patent is:

1. A solenoid operated valve for controlling the flow of corrosive liquids, such as hair waving solutions, and having parts exposed to the liquid which are resistant to the corrosion thereof, said valve comprising a body of non-magnetic and corrosion resistant material having a vertically disposed cylindrical valve chamber therein provided with inlet and outlet ports therefor, the outlet port being at the bottom of the valve chamber, a cylindrical valve member in the body for opening and closing the outlet port, said valve member being urged towards the outlet

port by gravity, said valve member comprising a magnetizable member and a non-magnetic and corrosion resistant envelope encasing the magnetizable member, and a coil winding for magnetizing said magnetizable member to effect opening of the valve.

2. A solenoid operated valve for controlling the flow of corrosive liquids, such as hair waving solutions, and having parts exposed to the liquid which are resistant to the corrosion thereof, said valve comprising a body of non-magnetic and corrosion-resistant material having a vertically disposed cylindrical valve chamber therein provided with inlet and outlet ports therefor, the outlet port being at the bottom of the valve chamber, a cylindrical valve member in the body for opening and closing the outlet port, inclined vanes on the valve member, projecting outwardly therefrom to space the valve member from the wall of the valve body chamber and to impart a spinning motion to the same when the valve is opened and liquid flows through it, said valve member being urged toward the outlet port by gravity, said valve member comprising a magnetizable member and a non-magnetic and corrosion-resistant envelope encasing the magnetizable member, and a coil winding for magnetizing said magnetizable member to effect opening of the valve.

3. A valve for a bottle-filling machine which comprises a tubular valve housing of non-magnetic and non-corroding material, having an upright chamber therein, there being a valve seat at the lower end of the chamber, a valve member having an elongated hollow upright body of non-magnetic and non-corroding material in said chamber, there being a valve face at the lower end of the valve member engageable with the valve seat, a plurality of spaced lugs on the sides of the valve member to space the body of the valve member from the sides of the chamber, a plug of magnetizable material inside of and completely encased within the hollow body of the valve member, a solenoid coil surrounding the chamber, and means for energizing the solenoid coil to raise the valve member from the valve seat to open the valve.

4. A valve for a bottle-filling machine which comprises a tubular valve housing of non-magnetic and non-corroding material, having an upright chamber therein, there being a valve seat at the lower end of the chamber, a valve member having an elongated hollow upright body of non-magnetic and non-corroding material in said chamber, there being a valve face at the lower end of the valve member engageable with the valve seat, a plurality of spaced lugs on the sides of the valve member to space the body of the valve member from the sides of the chamber, the lugs being elongated and inclined to the axis of the valve member to cause the valve member to turn when the valve member is raised from the valve seat and liquid flows through the valve, the lugs being formed in two spaced groups, one group being adjacent the upper end of the valve member and the other group being adjacent the opposite end of the valve member, the groups of lugs maintaining the valve member upright inside the chamber, a plug of magnetizable material inside of and completely encased within the hollow body of the valve member, a solenoid coil surrounding the chamber, and means for energizing the solenoid coil to raise the valve member from the valve seat to open the valve.

5. A valve for a bottle-filling machine which comprises a tubular valve housing of non-magnetic and non-corroding material, having an upright chamber therein, there being a valve seat at the lower end of the chamber, a valve member having an elongated hollow upright body of non-magnetic and non-corroding material in said chamber, there being a valve face at the lower end of the valve member engageable with the valve seat, a plurality of spaced lugs on the sides of the valve member to space the body of the valve member from the sides of the chamber, a plug of magnetizable material inside of and completely encased within the hollow body of

the valve member, a solenoid coil surrounding the chamber, means for energizing the solenoid coil to raise the valve member from the valve seat to open the valve, a filling tube connected to the lower end of the chamber and extending downwardly therefrom, the means for energizing the solenoid comprising a switch and a switch actuator connected to the switch, the switch actuator having a portion adjacent the filling tube, means for raising a bottle to a position in which the filling tube projects into the bottle and the mouth of the bottle engages the actuator to actuate the switch to a valve-open position, there being an air vent opening between the filling tube and the neck of the bottle, and means for supplying liquid to the valve chamber from a tank in which the level of liquid is at the height of the neck of the bottle when in said position, whereby liquid flows into the bottle until the bottle is filled to the neck and the valve closes to shut off the flow of liquid through the valve when the bottle is lowered to release the switch actuator.

6. A bottle-filling machine of syphon type which comprises a tank, means for maintaining a substantially constant head of liquid in said tank, a syphon tube having one end extending below the liquid in the tank, a hollow valve housing connected to the other end of said syphon tube, a valve member inside the valve housing, said valve member comprising a plug of magnetizable material, a solenoid winding around the housing, a filling tube extending from the valve body downwardly to below the liquid level, means for raising a bottle to a filling position at which the filling tube extends into the bottle and the neck of the bottle is at the liquid level in the tank, there being an air-venting space between the filling tube and the neck of the bottle, and switch means for energizing the solenoid coil when the bottle is raised to said position to actuate the valve member to valve open position, whereby liquid flows from the tank into the bottle until the level of liquid in the bottle reaches the neck of the bottle and the syphon head is zero.

7. A solenoid operated valve for controlling the flow of corrosive liquids and having parts exposed to the liquid which are resistant to the corrosion thereof, said valve comprising a tubular valve housing of non-magnetic and corrosion resistant material having an upright chamber therein and a valve seat at the lower end thereof, a vertically movable valve member in said chamber having an elongated hollow body of non-magnetic and corrosion resistant material, the lower end of the valve member having a valve face engageable with the valve seat, a plug of magnetizable material within and completely encased by the hollow body, and a solenoid coil for magnetizing the magnetizable member for raising the valve member to open the same.
- 15 8. A bottle-filling machine which comprises a tank, means for maintaining a substantially constant head of liquid in the tank, a siphon tube having one end extending into the liquid in the tank, a valve in said siphon tube, a spout attached to the other end of the siphon tube and extending downwardly to a level below the liquid level in the tank, means for raising a bottle to a filling position at which position the filling tube extends into the bottle through the neck thereof, there being an air venting space between the spout and the neck of the bottle, and means for opening the valve when the bottle is in filling position, whereby liquid flows from the tank into the bottle until the level of the liquid in the bottle is at the level of the liquid in the tank, the siphon head then being zero.
